UNITED STATES PATENT OFFICE.

JOHN SOMMER, OF PEORIA, ILLINOIS, ASSIGNEE TO KEYSTONE STEEL & WIRE COMPANY, OF SOUTH BARTONVILLE, PEORIA, ILLINOIS, A CORPORATION OF ILLINOIS.

BALE-TIE MACHINE.

1,393,178.

Specification of Letters Patent.

Patented Oct. 11, 1921.

Application filed January 28, 1919, Serial No. 273,586. Renewed August 27, 1921. Serial No. 496,132.

To all whom it may concern:

Be it known that I, JOHN SOMMER, a citizen of the United States, residing at Peoria, in the county of Peoria and State of Illinois, 5 have invented new and useful Improvements in Bale-Tie Machines, of which the following is a specification.

This invention has reference to bale-tie machines, and it has for its principal object 10 to provide an endless movable element to which is attached a plurality of twisting mechanisms, each arranged during its travel to grip a feed-wire, sever the front end portion of an unformed bale-tie from the rear 15 end portion of a formed bale-tie, draw the feed-wire through the machine, bend the end of the wire into a loop, twist the looped end to the body of the wire, and discharge the completed bale-tie into a trough or other 20 receiving means.

The invention has for a further object to move the endless movable element in a horizontal plane; the twisting mechanisms operating during their travel down one side of 25 the machine, and back the other, to form the bale-ties from continuous feed-wires, sever the formed bale-ties from the stock and discharge the same onto some suitable receiving means.

30 Each twisting mechanism comprehends a carriage in which is rotatably mounted a twisting element; wire gripping and severing means; means for removing the looped and twisted end of the bale-tie from the 35 twisting element; means to discharge the tie after the twisting operation, and means for operating the several mechanisms in timed relation with respect to each other, whereby the operation of forming bale-ties is continuous.

That the invention may be more fully understood reference is had to the accompanying drawings forming a part of the description, in which:—

45 Figure 1 is a greatly reduced side elevation of a bale-tie machine (partly broken away) embodying my invention;

Fig. 2 is a plan view of Fig. 1;

50 Fig. 3 is a detail vertical sectional view as the same would appear, if taken on the line 3—3 of Fig. 2;

Fig. 4 is a detail vertical sectional view as the same would appear, if taken on the line 4—4 of Fig. 2;

Fig. 5 is a detail in plan, on a somewhat 55 larger scale than is shown in Fig. 2, with parts removed to illustrate the endless movable element and one of the carriages movable thereby on which is mounted the twisting mechanism;

Fig. 6 is a detail in plan looking up from the underside of the bed of the machine, showing the arrangement of the racks, or gearing for actuating the operating parts on the carriages;

Fig. 7 is a detail cross-section as the same would appear if taken on the line 7—7 of Fig. 6;

Fig. 8 is a detail cross-section as the same would appear if taken on the line 8—8 of Fig. 6;

Fig. 9 is a detail cross-section as the same would appear if taken on the line 9—9 of Fig. 6;

Fig. 10 is a detailed plan view of one of 75 the carriages, the parts shown in positions, with the cutter about to sever the rear end of a formed bale-tie from the stock, and the gripper in the act of gripping the stock;

Fig. 11 is a front elevation of Fig. 10;

Fig. 12 is a plan view similar to Fig. 10 and of the same parts, except that the cutter has operated and the end of the wire stock has been looped about the twisting member, preparatory to the twisting operation;

Fig. 13 is a front elevation of Fig. 12;

Fig. 14 is an end elevation, of a carriage and operating parts, as the same would appear looking at Fig. 10, on the line 14—14 of Fig. 10;

Fig. 15 is an elevation, in cross-section, as the same would appear if taken on the line 15—15 of Fig. 10;

Fig. 16 is an elevation, in cross-section, as the same would appear if taken on the line 16—16 of Fig. 10;

Fig. 17 is an elevation of one of the intermittent bevel gear wheels, as the same would appear on the line 17—17 Fig. 10;

Fig. 18 is an elevation of the companion 100 gear wheel, to that shown in Fig. 17, and as the same would appear on the line 18—18 Fig. 10, and

Fig. 19 is a detail view showing the twisting element and the looped and twisted end 105 of a bale tie.

Like characters of reference denote corresponding parts throughout the figures.

The main supporting frame for the machine comprises the pair of spaced longitudinally disposed angle iron bars 1. These bars are connected to headers 2 secured respectively to the standards 3 and braces 4, which, in turn are connected to the floor rails 5.

At or near the left hand end of the machine, looking at Figs. 1 and 2, and supported by bars 1 is a bearing support 6 composed of the upper and lower castings 7 and 8 bolted together and to said bars 1. At or near the right hand end of the machine, looking at Figs. 1 and 2, and supported by bars 1 is a bearing support 9 composed of the upper and lower castings 10 and 11.

Connecting the castings 7 and 10 of the supports 6 and 9, respectively, are a pair of spaced rails 12 and 13 which have corresponding rounded ends 14. Connecting the castings 8 and 11 of the said supports 6 and 9, respectively, are a pair of spaced rails 15 and 16 which have corresponding rounded ends 17. The rails 15 are spaced below and in the same vertical plane with the rails 12, and the rails 16 are spaced below and in the same vertical plane with the rails 13.

The opposite straight stretches of the rails 12, and the opposite rounded ends thereof 30 are duplicates; this is also true of the opposite straight stretches of the rails 13, and the opposite rounded ends thereof, as very plainly seen in the plan view Fig. 6, looking up from the under side of the bed. For 35 instance, the under side of the rounded ends 14 of the rails 13 are provided with the rather long spiral racks 18, and along the under side of the straight portions of said rails 13 between the rounded ends, and approximately midway therebetween are also provided the rather long spiral racks 19, which are connected with the racks 18 by the connecting tooth-webs 20. The under-side of the opposite straight stretches of the 45 rails 12, near one end, are provided with the oppositely arranged short spiral racks 21 and 22, and at a suitable point on the under-side of the rounded ends of the rails 12 are provided short spiral racks 23, the teeth of 50 which are arranged to correspond to the teeth of the racks 21, and said racks 21, 22 and 23 are connected with each other by the connecting tooth-webs 24.

On the rail 16, see Fig. 1, there is provided an elongated cam-lug 24'. This lug, as will be seen, is located approximately at the juncture where the straight stretch of the rail merges into the rounded end, and this arrangement is duplicated at the opposite diagonal corner of the machine. On 55 the rail 15, see Figs. 1 and 5, there is provided a comparatively short cam-lug 25. This lug, like lug 24', is located approximately at the juncture where the straight stretch of the rail merges into the rounded

end, and this arrangement is also duplicated at the opposite diagonal corner of the machine.

In the bearing support 6 is journaled the short vertical shaft 26, on the lower end of 70 which is carried a driving sprocket wheel 27, and on the upper end of which is carried the bevel gear wheel 28, meshing with a bevel gear pinon 29 on one end of a horizontally disposed counter-shaft 30, journaled at its 75 outer end in the bearing support 6' and at its inner end in a bearing support 31. In the bearing support 9 is journaled the short vertical shaft 32, on the lower end of which is carried a driven sprocket wheel, or idler 80 33. Engaging the sprocket wheels 27 and 33 and traveling therebetween is the sprocket chain 34.

Power may be imparted to the counter shaft 30, as follows: 35 is a motor suitably supported on the base of the machine, and on the motor shaft is a pulley wheel 36, driving a belt 37, operating a driving pulley wheel 38 on a driving shaft 39, which also carries a pulley wheel 40 operating a belt 41 which in turn operates the drum 42 of a clutch on the counter-shaft 30. The friction driving part 43 of this clutch is splined on the shaft 30, whereas the drum 42 rotates loosely on said shaft, and said driving part 45 95 43 has a grooved sleeve 44 to which may be connected any lever operating means (not shown) which may be convenient and desirable to enable the operator to control the operation of the machine. The motor 35 100 may be connected with a source of current supply and controlled in any suitable manner.

Thus far I have described the supporting means for the operating parts; driving 105 mechanism, and endless movable element to which the carriages, to be described, are connected and by means of which the carriages and operating means thereon are caused to traverse the machine bed and manufacture the bale-ties. I will now describe the carriages and their mode of operation, it being understood that each carriage is a duplicate of the others, and therefore the description of one and its mode of operation will suffice for all. In the present arrangement three carriages are employed having a fixed relation relative to each other and connected with the chain 34.

The carriage is designated 45 and comprises the matching cast sections 46 and 47 suitably bolted together. The carriage, at its opposite ends, has up-standing bearings 48 and 49 in which are carried spindles 50 and 51. On the upper ends of said spindles are carried rollers 52 which roll against the inside matching faces of the rails 12 and 13, and on the lower ends of said spindles are carried rollers 53 which roll against the inside matching faces of the rails 15 and 130

16, see Figs. 14, 15, and 16. To the lower end of the spindle 50 is connected the chain 34, see Figs. 11 and 13.

54 and 55 designate coacting wire gripping jaws, see Figs. 10 to 13 and 16. These jaws are pivoted on a common pivot pin 56 and the operative position of the jaw 54 is yieldingly maintained by the spring 57. The jaw 55 is normally out of operative position and is moved to operative position by means of a roller 58 carried thereby which moves over the cam-lug 24'. When the jaws 54 and 55 are in operative position they engage a bale-tie wire to feed it through the machine. The jaw 54 has an extension 59 with which coöperates the combined cutting and gripping end 60 of a member 61 carried on the end of a shaft 62, on which is a bevel gear pinion 63 meshing with a bevel gear pinion 64 on a shaft 65, which also carries a segment gear 66. Also on the said shaft 65 is carried a disk 67 having an eccentrically located pin 68 which moves in a suitably formed sinuous groove 69 arranged in the end of a pusher bar 70 having the forked end 71. Said bar is guided in its longitudinal movement by means of a pin 72, which it carries, and which moves back and forth in a slot 73 arranged longitudinally in a covering plate 74, also provided with a forked end 75. The crotch of the forked end 71, in the pusher bar, is normally in axial alinement with a slotted twisting member 76, on the body of which is arranged a slotted segment gear wheel 77.

The segment gear wheel 66 slides in mesh with the tooth-web 24 on the rail 12, until the wheel 66 coincides with either of the racks 21, 22 or 23 when rotation is imparted 40 to said gear wheel and parts associated therewith. The same is true of the segment gear wheel 77 on the twister member, which slides in mesh with the tooth-web 20 on the rail 13, until the wheel 77 coincides with 45 either of the racks 18 or 19 when rotation is imparted to said gear wheel and parts associated therewith.

To the inner end of the twisting member 76 is eccentrically connected an elongated twisting stem 78 which has the hooked end 79. The cutting portion of the end 60 of member 61 coacts with the end of the twisting member 76 when severing the bale-tie-wire in two, see Fig. 11, as will be further explained.

To remove the looped and twisted end of a bale-tie from the hooked end 79 of twisting stem 78, I provide the bell-crank-shaped member 80 fulcrumed at 81, the short arm 60 portion of which carries a roller 82 adapted to roll over the cam-lugs 25 for operating said member. A spring 83 returns the member to the position seen in Fig. 16, after each operation.

65 During the time when the segment gear

wheel 77 is traveling with the carriage 45, between the racks 18 and 19, the tooth-web 20 on the rail 13 enters the slot 84 and holds the gear wheel against rotation. This gear wheel rotates always in one direction. This 70 is not true of the gear wheel 66 which rotates in one direction, when its teeth mesh with the racks 21 and 23, and in a reverse direction when its teeth mesh with the rack 22, and the tooth-web 24 entering a tooth in 75 said segment wheel 66 holds the gear wheel against rotation until it coincides with the racks 21, 22 and 23.

Reference to Figs. 1, 2 and 5 discloses that bale-tie-wires A are fed down the opposite 80 sides of the machines, in opposite directions, being drawn by the carriages 45 from suitable reels (not shown) and through the straightening devices 85. The idea being, as stated in the preamble, to manufacture or 85 produce bale-ties as the carriages traverse the opposite sides of the machine. Each succeeding carriage picking up the bale-tie-wire A immediately upon the completion of 90 a tie by the preceding carriage, when the completed tie is severed from the bale-tie-wire stock and discharged onto or into some suitable receiving means.

In operation, describing the action of one carriage, all being the same, and referring 95 to Figs. 1, 2, 5 and 6 as general figures to illustrate such operation, the carriage as it comes toward you around the right hand end of the machine will present the jaws 54 and 55 in an open position, as seen in Fig. 100 16, to permit the bale-tie-wire stock A to enter between said jaws. The roller 58 on the jaw 55 will roll over the cam lug 24' which will force the jaw 55 to grip the wire A between it and the jaw 54 and draw the 105 wire through the machine.

The gear wheel 66 is rotated as it is brought into coincidence with the rack 22 which will operate bevel gear wheels 63 and 64 to rotate the member 61 from the position seen in Fig. 11, to the position seen 110 in Fig. 13, and during such movement the end of the bale-tie-wire-stock is looped over the hooked end 79 of the stem 78, as at B, and the end caught between the gripping 115 end of the member 61 and the jaw 55. This gripping operation occurs about the same time the roller 58 leaves the cam lug 24', which permits the jaw 55 to drop by action of gravity to an inoperative position. The 120 movement of the member 61 from the position shown in Fig. 11 to the position shown in Fig. 13 will sever the rear end of a formed bale-tie from the stock, after the initial operation of drawing the stock A 125 into the machine, and during the successive operations, as the carriages succeed each other in their movement through the machine.

When the segment gear wheel 77 coincides 130

with the rack 19 the twisting member 76 is caused to rotate and it in turn rotates the stem 78 twisting the looped end B with the body of the wire A, as at C, see Fig. 19. 5 After the twisting operation, and when the gear wheel 66 coincides with the rack 22, the bevel gear wheels 63 and 64 are partially rotated returning the member 61 to a position approximately midway between 10 the positions shown in Figs. 11 and 13, about which time the roller 82 on the bell-crank-arm 80 rides on the cam lug 25 which will swing the long end of arm 80 downwardly and the same engaging with the 15 twisted end of the bale tie, will force it off of the hooked end 79 of stem 78. The hooked end of said stem having stopped in a position pointing downwardly and outwardly. When the gear wheel 66 is brought 20 coincident with the rack 23 the member 61 is caused to be moved the remainder of the distance to position it, as seen in Fig. 11. The rack 18, engaged by the gear wheel 77 will return the twister and its hooked pin 25 to initial position.

At or about the time that the bell-crank-arm 80 is operated to eject the formed and twisted end of the bale-tie off of the hooked end 79 of the stem 78, the next carriage has 30 reached the position where the gear wheel 66 will be rotated by the rack 22 to operate the member 61 which severs the rear end of the formed bale-tie from the stock A. Immediately upon the severing of the formed 35 tie from the stock, the pusher bar 70 is operated, whereby the plain end of the tie is ejected from the twister 76 simultaneously with the ejecting of the formed end of the tie from the hooked end of the stem 78. 40 The operation of the pusher bar 70 from the gear wheel 66, Fig. 14, it is believed is understood and does not require further explanation.

It is obvious that various changes may be 45 made in the machine without departing from the spirit and scope of the invention, and I do not want to be limited to the precise details except as I may be limited in the appended claims.

50 **What I claim is:—**

1. In a bale-tie-machine, in combination, a bed including two sets of spaced rails, one above the other, each of said upper rails provided at predetermined points with 55 racks, an endless member movable on said bed, means for operating said endless member, a plurality of carriages connected to move with said endless member, gearing on said carriages arranged to be actuated by said racks, a wire cutting, looping and gripping member operated from said gearing, and a twisting member operated from said 60 gearing.

2. In a bale-tie-machine, in combination, 65 a bed including two sets of spaced rails,

one above the other, each of said upper rails provided at predetermined points with racks, each of said lower rails provided at predetermined points with cam lugs, an endless member movable on said bed, means 70 for operating said endless member, a plurality of carriages connected to move with said endless member, gearing on said carriages arranged to be actuated by said racks, an initial wire gripping means on each 75 carriage operated from certain of said cam lugs, a wire cutting, looping and gripping member operated from said gearing, a twisting member operated from said gearing, an ejecting member operated from certain of 80 said cam lugs, and an ejecting member operated from said gearing.

3. In a bale-tie-machine, in combination, a bed including a set of spaced rails, each rail provided at predetermined points with 85 toothed racks, the sets of teeth connected by a tooth-web, an endless member movable on said bed, means for operating said endless member, a plurality of carriages connected to move with said endless member, 90 gearing on said carriages arranged to be actuated by said racks when coincident therewith and to be held inoperative by said tooth-web between said racks, a wire cutting, looping and gripping member operated 95 from said gearing, and a twisting member operated from said gearing.

4. In a bale-tie-machine, in combination, a frame, a horizontal bed arranged thereon, an endless track on said bed, including 100 toothed rails, traveling supports mounted on said rails, means for moving said supports, gearing on said supports arranged to be operated at predetermined intervals by engagement with the teeth on said rails, wire cutting, 105 looping and gripping means on said supports and arranged to be operated by said gearing, and twisting means on said supports also arranged to be operated by said gearing.

5. In a bale-tie-machine, in combination, a frame, a horizontal bed arranged thereon including toothed rails, an endless movable member, a driver for said member, a motor on the frame, a clutch controlled transmission between said motor and said driver, a plurality of supports on said bed and connected in spaced relation with said member to travel therewith, gearing on said supports arranged to be operated by engagement 115 with the teeth on said rails, wire cutting, looping and gripping means arranged to be operated from said gearing, and twisting means also arranged to be operated from said gearing.

6. In a bale-tie-machine, in combination, a frame comprising two sets of endless rails, one set above the other and next adjacent thereto, the upper set having toothed racks spaced at predetermined points thereon, and 120 125 130

the lower set having cam-lugs spaced at predetermined points thereon, substantially for the purposes described.

7. In a bale-tie-machine, in combination, 5 a frame comprising two sets of endless rails, one set above the other and next adjacent thereto, the upper set having spiral toothed racks spaced at predetermined points thereon, gearing movable successively into engagement with said racks, certain of said racks arranged to rotate gearing in directions opposite to the other racks, and the lower set of rails having cam lugs spaced at predetermined points thereon, substantially 10 for the purposes described.

8. In a bale-tie-machine, in combination, 15 a movable support, an initial wire gripping means thereon, an intermittently operated twister, a hooked stem eccentrically connected with said twister, a combined cutter and gripper arranged to sever a wire, loop one end about said hooked stem and finally grip the looped end with the body against said initial gripping means, and means for operating the twister, and combined cutter and gripper in timed relation with each other.

9. In a bale-tie-machine, in combination, 20 a movable support, an initial wire gripping means thereon, an intermittently operated twister, a hooked stem eccentrically connected with said twister, a combined cutter and gripper arranged to sever a wire, loop one end about said hooked stem and finally grip

the looped end with the body against said initial gripping means, means for operating 35 the twister, and combined cutter and gripper in timed relation with each other, means for ejecting the looped and twisted end of the bale tie off said hooked stem, and means for ejecting the wire from the twister. 40

10. In a bale-tie-machine, in combination, 45 endless rails, certain rails having toothed segments and certain rails having cam-lugs, a support movable on said rails, an endless chain, a connection between said support and said chain, an initial wire gripping means having a roller to engage a cam lug to operate said gripping means, a twister, gearing for operating the twister, said gearing adapted to engage certain toothed segments, 50 a hooked stem eccentrically connected with said twister, a combined cutter and gripper arranged to sever a wire, loop one end about said hooked stem and finally grip the looped end with the body against said initial gripping means, gearing for operating said cutter and gripper, said gearing adapted to engage certain toothed segments, a member for ejecting the looped end of the bale-tie off 55 of said hooked stem, said member having a roller to engage a cam-lug to operate said member, and a member for ejecting the wire from the twister, said member operated from said last mentioned gearing.

JOHN SOMMER.
